ICE TRAY

Alvar Lenning, Stockholm, Sweden, assignor, by
mesne assignments, to Servel, Inc., New York,
N. Y., a corporation of Delaware

Application February 23, 1937, Serial No. 127,002
In Germany March 6, 1936

12 Claims. (Cl. 62—108.5)

My invention relates to ice trays and grid structures for use in household refrigerators, and has for its object the provision of an improved ice tray to facilitate the removal of its frozen contents. More particularly, it is an object of my invention to provide an improved ice tray and a device cooperating therewith to facilitate the removal of a grid structure and ice pieces therefrom. A further object of my invention is to provide an improved flexible grid structure for use in the production of ice pieces in refrigerators, whereby the ice pieces are readily removed therefrom by a simple twisting action of the grid structure.

The invention, together with the objects and advantages thereof, will become apparent from the following description taken in conjunction with the accompanying drawing forming a part of this specification, and of which Fig. 1 is a plan view of an ice tray and a grid structure embodying my invention; Fig. 2 is a longitudinal sectional view taken on line 2—2 of Fig. 1; Fig. 3 is a front view of the ice tray and grid structure shown in Figs. 1 and 2; and Fig. 4 is a fragmentary plan view of the ice tray shown in Fig. 1 with the grid structure omitted to illustrate parts of the ice tray more clearly.

In Fig. 1, a grid structure 10 is shown positioned in an ice tray 11 having a resilient bottom and side walls. The tray 11 is preferably made of suitable thin metal, such as aluminum or stainless steel, for example, and about the upper edges of the side walls is provided an outward extending flange 12.

The grid structure 10 embodying my invention comprises two zigzag-shaped longitudinally extending partitions 13 disposed between a straight longitudinal partition 14. The partitions 13 and 14 are arranged to form triangular-shaped ice pieces, and the ends of the partitions are secured to cross members 15 which extend into the ends of the tray and are provided with spaced flanges 16 and 17 overlying the upper edges of the tray. The flanges 16 and 17 serve as handles for twisting the grid structure to cause the triangular-shaped ice pieces to peel from the partitions 13 and 14 after the grid structure has been removed from the tray with the ice pieces clinging thereto. Each of the cross members 15 is also provided with a larger central flange 18 which extends over one of the short end walls of the tray to facilitate the removal of the grid structure from the tray, as will be described hereinafter.

In accordance with my invention the tray 11 is so formed that one wall is deformable and capable of being stretched or elongated, and a device is

provided to elongate the wall and break the bond produced between the ice and the wall of the tray. The device is preferably so constructed that, in addition to breaking the bond between the ice and the wall of the tray, the device is also capable of exerting a separating force between the grid structure and the tray body. I accomplish this by forming the tray 11 in such a manner that one end wall is corrugated or zigzag-shaped, as shown at 19 in Figs. 1 and 4. The flange at the upper edge of the end tray wall is broken away adjacent the indented or zigzag portion 19 thereof, and at each side of the indented portion 19 the flange is looped to form sleeves 20 adapted to receive a pin 21.

To the pin 21 is secured an end of a relatively broad lever 22 which is of such width that it extends between the inner ends of the sleeves 20. The lever 22 is provided with a central slot 23 which is at right angles to the pin 22, and from the slot the two sides or halves of the lever slope inwardly, as shown most clearly in Fig. 1. Thus, by slotting the lever and providing the sloping sides, the lever is bowed or arched and is more or less wedge-shaped.

In using the grid structure 10 and the tray 11 just described, the grid is positioned in the tray and the latter is filled with water. After the water has been frozen and ice pieces have been produced by placing the tray in a cooling unit of a refrigerator, the tray is taken out of the cooling unit with the lever 22 in the vertical position shown in Figs. 2 and 3. The flexible lever 22 is then pulled upward toward the horizontal position shown in Fig. 4. With such upward movement of the lever the highest points of the flexible sloping sides adjacent the slot 23 bear against the underside of flange 18. Since the grid structure 10 and ice pieces are frozen solidly in the tray 11, the flange 18 remains in a fixed position whereby the sloping sides of the lever are flexed and bear against the inner ends of the sleeves 20. Due to this wedge action of the lever the sleeves 20 are forced outwardly and away from each other whereby the end wall of the tray is expanded or elongated and the upper edges of the tray walls are deformed.

The deformation or distortion of the end tray wall causes the tray wall to break its bond with the ice. After the bond between the front tray wall and ice has been broken and the upward movement of the lever 22 is continued, a separating force is exerted between the grid structure 10 and the tray 11. This is readily accomplished by giving the lever such a curvature that the lever 55

exerts an upward force on the flange 18 and causes the grid structure 10 to separate from the bottom of the tray with the ice pieces clinging thereto. When the ice bond is once broken at the front 5 end wall of the tray, the continued upward movement of the lever causes a gradual peeling of the ice from the tray walls and along the bottom of the tray, whereby the removal of the grid structure and ice is readily effected.

10 By holding the flanges 16 and 17 of the grid cross-members 15 and twisting the grid by turning the members 15 back and forth in opposite directions, the ice pieces are readily released by the twisting action of the partitions 13 and 14.

15 In view of the foregoing, it will now be understood that by the single continued upward movement of the tongue-shaped lever 22, the bond between the ice and the front end wall of the tray is first broken and subsequently the grid structure 20 with the ice pieces clinging thereto is separated from the tray. By constructing the tray and the device so that the ice bond is first broken, the relatively great force that would otherwise be necessary to separate the ice and grid structure 25 from the tray is reduced considerably. Since the curvature given the lever 22 adjacent the end fixed to the pin 21 is similar to that of an eccentric or cam, peeling or shearing of the ice readily takes place about all of the tray walls and the tray 30 bottom with continued upward movement of the lever after the ice bond has once been broken. The eccentricity of the lever effectively raises the grid structure and ice with such peeling and shearing and, since the force applied to the lever is 35 multiplied many times due to the wedging action of the lever, very little effort is required on the part of the user to remove the grid structure and ice pieces from the tray. Since both ends of the grid structure 10 are similar, the grid structure 40 can be positioned in the tray 11 with either end disposed at the front end wall of the tray.

Although I have shown and described a particular embodiment of my invention, it will be apparent that modifications and changes may be made 45 without departing from the spirit and scope of my invention.

What is claimed is:

1. Apparatus for producing ice pieces comprising a tray body adapted to hold water to be 50 frozen and having resilient bottom and side walls, one of said side walls being deformable, a grid member removably fitting into said tray body, and mechanism including a member extending lengthwise of said deformable wall operative to 55 bear against a part of said grid and parts of said tray to deform said one wall and break the bond between such wall and the ice.

2. Apparatus for producing ice comprising a tray adapted to hold water to be frozen and having bottom and side walls, one of said side walls being deformable, a grid member removably fitting into said tray, and mechanism including a flexible member extending lengthwise of said deformable wall adapted upon movement thereof 60 to contact a part of said grid member and parts of said tray to deform said one side wall to break the bond between such wall and the ice.

3. Apparatus for producing ice comprising a tray adapted to hold water to be frozen and having 70 bottom and side walls, one of said walls being deformable, a grid member removably fitting into said tray, and mechanism including a cam-shaped member extending lengthwise of said deformable wall operative first to deform said one wall to 75 break the bond between such side wall and the ice.

and subsequently to exert a separating force between said grid member and said tray.

4. An ice tray for refrigerators adapted to hold water to be frozen and having a resilient bottom and side walls extending upward from the bottom, 5 the side walls being rigidly connected together at their ends, one of the side walls being so shaped and formed that it is stretchable, and mechanism including a member extending in the direction of said stretchable side wall and arranged to act 10 on said stretchable side wall to elongate the latter and cause outward spreading of the side walls connected to the ends of the stretchable side wall and thereby break the ice bond.

5. Apparatus for producing ice pieces including 15 a tray adapted to hold water to be frozen and having a resilient bottom and side walls extending rigidly connected together at their ends, a grid member removably fitting in the tray, one of the 20 side walls being so shaped and formed that it is expandable in the direction of its length, mechanism operative to cause stretching of said expandable wall and effect outward spreading of the side walls connected to the ends of said expandable wall, and said mechanism also being operative to lift the grid member bodily away from the bottom of the tray when it is being operated to cause stretching of said expandable wall.

6. In combination with an ice tray for refrigerators adapted to hold water to be frozen and having a resilient bottom and side walls, one of said side walls being so shaped and formed that it is expandable, a stretchable member arranged to extend in the direction of said expandable wall and having the ends thereof adapted 30 to cooperate with said tray at spaced points, and said stretchable member being so constructed and arranged that, when force is applied to an intermediate region thereof, its ends spread apart to 40 cause lengthening of said expandable wall and thereby break the ice bond between the expandable wall and ice contained in said tray.

7. Apparatus for producing ice pieces comprising 45 an element including an upstanding deformable wall, spaced projections on said element and relatively movable with deformation of said wall, and mechanism extending lengthwise of said deformable wall for forcing said projections away from each other to deform said wall and break 50 an ice bond.

8. Apparatus for freezing matter including an element having a deformable wall, a flexible or extensible member extending in the direction of said deformable wall and having portions thereof adapted to cooperate with said element at spaced points, and said flexible or extensible member being so constructed and arranged that, when force is applied to an intermediate region thereof, its ends spread apart to cause deformation of 60 said wall to break a frozen bond.

9. Apparatus for producing ice including an element having a deformable wall, a resilient member extending in the direction of said deformable wall and having the ends thereof adapted to 65 cooperate with said element at spaced points, and said resilient member being so constructed and arranged that, when force is applied to an intermediate region thereof, its ends move away from each other to cause deformation of said wall.

10. Apparatus for freezing matter including an element having a deformable wall and spaced walls transverse to said deformable wall, said transverse walls spreading apart with deformation to said deformable wall, and mechanism in- 75

- cluding a member extending in the direction of said deformable wall and operable to act on said deformable wall to deform the latter and cause said transverse walls to spread apart.
- 5 11. Apparatus for freezing ice including a tray element and a grid element removably fitting in said tray element, one of said elements having a deformable wall, a flexible or extensible member extending in the direction of said deformable wall
- 10 and having portions thereof adapted to cooperate with said one element at spaced points, and said flexible or extensible member being so constructed and arranged that, when force is applied to an intermediate region thereof, its ends spread apart
- 15 to cause deformation of said wall and break an ice bond while said grid element is in said tray element.

12. Apparatus for freezing ice including a tray element and a grid element removably fitting in said tray element, one of said elements having a deformable wall, mechanism including a flexible or extensible member extending lengthwise of said deformable wall and having portions thereof adapted to cooperate with said one element at spaced points, said flexible or extensible member being so constructed and arranged that, when force is applied to an intermediate region thereof, 10 its ends spread apart to cause deformation of said wall to break an ice bond while said grid element is in said tray element, and said mechanism also being effective to bodily lift said grid element away from the bottom of said tray element.

ALVAR LENNING.
